RHEOSTAT CONTROL FOR A WINDOW FAN

Charles D. Visos, St. Louis, Mo., assignor to Knapp-Monarch Company, a corporation of Missouri

Filed May 6, 1957, Ser. No. 657,094

1 Claim. (Cl. 338—116)

This application relates to improvements in electrically operated fans and more particularly to new and improved speed control apparatus for such fans.

Several types of speed control devices for electrically operated fans are known in the prior art. Generally, such devices comprise power regulating means connected in circuit with the fan motor to the end that the speed of the fan, and hence its air handling capacity, may be controlled in a given manner. However, many of such prior art speed control devices have not proved fully satisfactory for the reasons described below.

One commonly used type of prior art speed control for an electric fan takes the form of a multi-position rotary switch which may be selectively actuated to two or more preset positions, as for example, low, medium and high, to enable the fan to operate in corresponding speeds. Manifestly, this fixed type of control is not very flexible in providing the variety of fan speeds which may be desired by the user. Further, such speed controls generally are relatively large and therefore cannot efficiently be mounted in the fan in the path of air currents to facilitate dissipation of the heat generated therein.

Accordingly, it is a general object of this invention to provide new and improved speed control means for electrically operated fans.

It is another object of this invention to provide speed control means for an electrically operated fan which is continuously variable from the lowest speed position to the highest speed position, and which therefore is adapted to provide a substantially large number of selectable fan speeds.

It is still another object of this invention to provide an improved speed control means for an electrically operated fan which is characterized by its compactness and which therefore may be positioned in the fan housing to enable dissipation of heat by air currents without detracting from the efficient operation or the attractiveness of the fan.

It is a further object of this invention to provide an improved speed control means for an electrically operated fan in which special provision is made for substantially reducing the problem of arcing in the control means.

It is a still further object of this invention to provide a new and improved speed control means for a fan, as described above, which is further characterized by its relative simplicity and its economy of construction and operation.

These and other objects are realized in accordance with a specific illustrative embodiment of this invention in which a continuously variable speed control device is connected in series with the fan motor and source of electric power. In accordance with a feature of this invention, the continuously variable speed control device is reduced in size by connecting the resistance windings of a plurality of rheostats in series between the fan motor and the power source.

Each rheostat comprises a brush placed in sliding contact with its resistance winding, so as to be variably adjustable over the entire range of the winding. Advantageously, two rheostat brushes are mechanically coupled to

2

each other, as by means of a contact spring, and the brushes are operated by a manually actuatable slide knob positioned on the fan housing. Thus, the adjustment of the slide knob to any of its relatively great number of positions between the high speed and low speed ends of the rheostats result in an equal number of variances of the motor and fan speed. Consequently, the invention enables the amount of air delivered by the fan to be selectively varied, as desired, to any amount within its capacity from a slight breeze to a full power air blast.

In accordance with a feature of another illustrative embodiment of the invention, any tendency of the speed control to arc, as may result from poor contact or loose brushes, is substantially eliminated by means of a shunt circuit connected between the low speed ends of each rheostat resistance winding. This novel shunt circuit is effective to reduce the voltage potential for creating an arc to zero when the speed control slide knob is at the extreme low speed position, and to a value of relatively few volts when the slide knob is at the extreme high speed position. Thus, at either extreme, and therefore at all intermediate speeds, the problem of arcing in the fan speed control of the invention is practically non-existent.

The above and other features of novelty which characterize the invention are pointed out with particularity in the claim annexed to and forming a part of this specification. For a better understanding of this invention, however, its advantages and specific objects attained with its use, reference is had to the accompanying drawing and descriptive matter in which is shown and described several illustrative embodiments of the invention.

In the drawing:

Figure 1 is a front elevational view of a preferred embodiment of fan assembly with parts broken away;

Figure 2 is a top plan view of the fan assembly shown in Figure 1;

Figure 3 is an enlarged cross sectional view of a multi-speed control device embodying the invention;

Figure 4 is a plan view of the multi-speed control device rheostat assembly with parts broken away;

Figure 5 is a transverse cross sectional view of the rheostat assembly taken substantially as shown on line 5—5 of Figure 4;

Figure 6 is a schematic diagram of the electrical control circuit in accordance with one embodiment of the invention; and

Figure 7 is a schematic diagram of the electrical control circuit in accordance with another embodiment of the invention.

Referring now to the drawing and more particularly to Figures 1 and 2, the reference character 10 indicates a fan assembly which includes a main frame 12 advantageously provided with a pair of panel members 14 and 16 slidably disposed at either end of frame 12. Panel members 14 and 16 are adapted to permit the fan assembly 10 to be used in various widths of window openings, and, to this end, the panel members are provided with horizontal elongated slots 18 adapted to cooperate with screws 19 in frame 12 to enable the width of the fan assembly to be adjusted as desired. However, it will be understood by those skilled in the art that the panel members may be removed for enabling the fan assembly to be used in a different manner, as, for example, a floor blower and the like.

A fan housing 20 is secured to the main frame 12 and extends outwardly therefrom for enclosing a plurality of fan blades 22 adapted to be driven by the shaft 23 of an electric motor 24. A large central opening 26 is provided adjacent fan blades 22 within the main frame 12, and suitable safety guards 28 are secured to housing 20 at both sides of fan blades 22. Thus, the fan blades

22 are mounted so as to propel air through the central opening 26 and the safety guards 28 when the fan is in operation in response to the energization of the electric motor 24. Suitable brackets 30 may be secured to the main frame 12 for mounting and supporting the electric motor and fan blade assembly.

At the upper end of housing 20 there is provided a handle 32 for enabling the fan assembly to be handled and transported as desired. Located at one side of handle 32 there is a control knob 34 which cooperates with a suitably marked plate 36 for enabling the fan to be automatically turned on and off at a desired temperature. The details of the thermostatic control which is connected to the control knob 34 are not shown as they are well known and do not form a part of the invention as such.

A slideable control knob 38 is provided at the other side of handle 32 for controlling the speed of the fan over a continuously variable range. Advantageously, a switch plate 40 is provided with control knob 38 and is marked for various speeds between the high and low speed markings for facilitating adjustment of control knob 38.

The multi-speed control assembly is shown in greater detail in Figures 3, 4, and 5 of the drawing. In accordance with a feature of this invention, the novel multi-speed control assembly comprises a pair of rheostats 42 and 44 having resistance windings 46 and 48 respectively wound upon a common resistor core 50. Advantageously, common resistor core 50 is formed of an insulating material and may be of cylindrical shape with an annular cross section as shown in Figure 5.

A brush 52 is positioned for sliding contact with resistance winding 46, and a brush 54 is positioned for sliding contact with resistance winding 48. The two brushes 52 and 54 are mechanically and electrically connected by means of a contact spring 56 which serves to urge each brush into contacting engagement with its associated resistance winding.

Advantageously, contact spring 56 is secured to the multi-speed control knob 38 to the end that adjustment of control knob 38 in the elongated slot 41 provided in switch plate 40 causes a corresponding adjustment of brushes 52 and 54 over their respective resistance windings. The control knob 38 is formed of an insulating material and in a preferred embodiment of the invention the control knob may be formed from plastic or hard rubber.

It is an aspect of this invention that the provision of two potentiometers connected in series by means of contact spring 56 in lieu of a single potentiometer construction enables the multi-speed fan control to be manufactured in a relatively compact manner. Thus, the two rheostats may be supported in a suitable housing 58 secured to the fan housing 20 by screws 60 and 62. The compact construction of the multi-speed control enables the latter to be placed in the fan housing in the path of air currents to thereby facilitate the dissipation of the heat generated therin. It further will be appreciated that this compact construction enables the multi-speed control to be advantageously positioned as described above without detracting from the efficiency of operation or the attractiveness of the fan.

In accordance with one circuit embodiment of the invention as shown in Figure 6, the high speed terminal of resistance winding 46 of potentiometer 42 is connected to a terminal of electric motor 24. The other terminal of electric motor 24 is connected to one side of a power plug 64, and the other side of power plug 64 is connected to the high speed terminal of resistance winding 48 of potentiometer 44. When the multi-speed control knob 38 is in the low speed position, or at the extreme right end of resistance windings 46 and 48 as shown in Figure 6, the brushes 52 and 54 are positioned on their respective resistance windings such that the potentiometers insert a maximum resistance in the series motor circuit. Under these conditions it will be appreciated that

the voltage across motor 24 will be at a minimum and that therefore the motor will operate at its lowest speed. As the control knob 38 is moved towards the high speed end of the potentiometers 42 and 44, correspondingly less resistance is inserted in the motor circuit by the potentiometers 42 and 44 with the result that the speed of the motor is correspondingly increased.

It will be understood by those skilled in the art that poor contact between the brushes and the resistance windings which, for example, may result from loose brushes, may cause arcing to take place between the brushes and the resistance windings of the rheostats. The voltage potential for creating an arc will be at its maximum when the multi-speed control knob 38 is in the extreme low speed position. The problem of arcing is substantially eliminated by means of the novel shunt circuit shown in Figure 7 of the drawing. The circuit of Figure 7 is similar to that of Figure 6 with the exception that the open or low speed terminals of rheostat resistance windings 46 and 48 are connected to each other by a shunt conductor 66. The effect of shunt conductor 66 is to reduce the voltage potential for creating the arc to zero when the speed control knob 38 is in the extreme low position, since conductor 66 provides a short circuit across the brushes, and to the order of approximately 15 or 20 volts, with a standard 115 volt input, when the speed control knob 38 is at the extreme high speed position. Manifestly, at either the low speed or high speed positions, and consequently at all intermediate positions, the problem of arcing is substantially eliminated.

Thus there has been shown and described a novel multi-speed control for an electric fan which permits the speed of operation of the fan to be adjusted in a continuously variable manner over the entire range from extreme low to extreme high speeds. Further, this unique fan speed control may be manufactured in a relatively compact and inexpensive manner, and still further the problem of arcing due to poor contact or loose brushes has been effectively resolved. It will be understood by those skilled in the art that modifications may be made in the construction and arrangement of the parts in the above described multi-speed fan control without departing from the real spirit and scope of the invention and that it is intended to cover by the appended claim any modified forms of structure or use of equivalents which may reasonably be included within their scope.

I claim:

In a fan structure of the type having a housing, a motor therein, and a fan driven by said motor to propel air through said housing, the improvement of a continuously variable speed control means for said motor comprising first and second rheostat means, a cylindrical core of insulating material, said first and second rheostat means comprising a pair of resistance coils wound in spaced axial alignment upon said cylindrical core, a pair of terminals, one for each resistance coil, adapted to be connected respectively to a source of power and said motor, and manually operable wiper means providing an electrically conductive path between said first and second rheostat means for selectively varying the resistance in the motor circuit to enable the speed of operation of said motor to be controlled as desired in a continuous manner over a predetermined range of speeds, said manually operable wiper means comprising a pair of spaced brushes positioned in axial alignment for sliding contact with their associated resistance coils, whereby the axially aligned arrangement of said coils and said brushes serves to minimize the depth of said speed control means to enable the latter to be placed within the housing adjacent said fan.
